HYDRAULIC CONTROL DEVICE

William Waterman, Chicago, Ill., and Donald A. Stark, Willoughby, Ohio; said Stark assignor to said Waterman

Application January 26, 1948, Serial No. 4,256

4 Claims. (Cl. 121—46.5)

1

This invention relates to hydraulic control devices and particularly to valve devices for controlling supply of hydraulic fluid to and discharge thereof from, an instrumentality wherein the discharge pressures may be high.

Among other objects, the invention aims to provide safety means under the control of the valve device for safely and easily effecting the discharge of high pressure fluid.

Another object is to provide separate means under the control of the valve device for assuming and holding, without leakage, high pressures and for relieving the valve device of this function.

A further object is to provide a control unit which in addition to the foregoing functions, is adapted independently to control the rate of supply and discharge of hydraulic fluid.

Other objects and advantages of the invention will become apparent from the following description of one illustrative device embodying the invention and shown in the accompanying drawings.

In said drawings:

Fig. 1 is a plan view of the device;

Fig. 2 is a side elevation thereof, taken from the plane 2—2 of Fig. 1;

Fig. 3 is a plan section taken on the plane 3—3 of Fig. 2;

Fig. 4 is an end elevation of the device taken from the plane 4—4 of Fig. 1;

Fig. 5 is a view similar to that of Fig. 1 but being partly sectioned on the plane 5—5 of Fig. 4;

Fig. 6 is an end view (inverted relative to Fig. 3), partly sectioned on the plane 6—6 of Fig. 1 to illustrate the flow regulator.

Fig. 7 is a diagram of a system to illustrate the function and operation of the valve device in hydraulic rams and the like; and

Fig. 8 is a fragmentary section on an enlarged scale of the pilot controlled check valve shown also in Fig. 3.

In hydraulic cylinders operating against a continuous force or load, the illustrative valve device 10 operates to control delivery of pump pressure to the single acting ram cylinder 11 (Fig. 7). The ram is held elevated or in extended position against the load by separate means capable of holding pressures created by the load or otherwise, without leakage, thereby in effect, locking the ram against downward or return creeping movement. The valve device thus has utility in hydraulic rams for lifting trucks and other apparatus. The valve is also adapted to control descent of the ram under its own load or weight; and when fully descended, the valve discharges or by-passes the pump 13 into reservoir 14 at practically no load.

2

The uses of hydraulic lifting and other rams are varied. One common use is for lift trucks wherein the load elevated by the ram may be very heavy and must often be held in elevated position during the movement of the truck, and often for substantial periods of time. The valve device is not, however, limited in its use to rams but may be employed wherever similar functions are required. For convenience the term "ram" will be employed in a broad sense to designate the operating instrumentality controlled by the valve device.

The "three-way" operation of the illustrative valve device 10 is effected in this instance by a longitudinally slideable spool-type valve member 21 (operated as presently described), to the valve chamber 22 of which supply from pump 13 is admitted through port 23. A spool type valve is advantageous because it may be balanced for easy operation, but it characteristically leaks and is therefore incapable of holding a ram against creeping or slow return travel. The aforesaid valve chamber communicates with passage 24 leading (as presently described) to the ram and to inlet port 25 of line 26 leading to the reservoir or fluid supply source.

In the position illustrated in Fig. 1 (i. e. neutral position) the restricted section 27 of the spool registers with port 25, thereby connecting the pump with discharge line 26 so that the pump operates at substantially no load. To connect the pump with the ram through passage 24, the valve spool is moved longitudinally (down in Fig. 3) until its enlarged portion 28 closes port 25. Intermediate the restricted and enlarged portions 27 and 28 the spool is advantageously tapered as at 29 to permit variation in rate of flow to the ram by throttling port 25, thereby controlling the speed of ram travel. The balance of the pump flow by-passes to the reservoir.

Line 30 leading to ram cylinder 11 is connected to valve block 31 at fitting 32 (Fig. 6). The latter in turn communicates as presently described with a passage or bore 33 extending longitudinally of the valve block and closed at one end by a plug. Passage 33 communicates with passage 24 through a cylindrical recessed socket 34 in the valve block in which is seated check valve unit 35 functioning to permit travel of fluid from the spool to passage 33 and the ram, but blocking return travel from the ram to the spool. Spring 37 prevents displacement of check ball 36 relative to its seat 38 regardless of the position of the device. Check valve unit 35 is sealed in recess 34 by sealing rings 39, and held therein against the bottom of the recess by screw plug 40. Fluid enters the check

valve unit through chamber 41 (in communication with passage 24) and leaves through the annular passage 42 around the unit which communicates with passage 33.

The latter passage also communicates with a check valve unit 43 which functions when closed, to lock the ram in elevated or extended position under load, thereby relieving spool 21 and its operating mechanism of the very substantial load of the ram and avoiding leakage around the spool which would otherwise ensue. Since check valve 35 prevents return flow from the ram through passage 24, the ram is held stationary in its extended position until opening of check valve unit 43.

The latter valve unit is advantageously seated in the cylindrical recess 45 located in the valve block so as to be intersected by bore 33, and is sealed therein by sealing rings 46 and held tightly against the bottom of the recess by a screw plug 47. The valve comprises a cylindrical shell 48 at the end of which is a valve seat 49 and port 51 communicating with the space 52 at the bottom of the recess which in turn communicates with passage 53 leading to the spool bore 54. Discharge from the ram passes from the annular space 55 around the valve body (in communication with passage 33) through a series of holes 56 in the valve body through port 51 and thence through the spool cylinder to discharge port 57 opening into discharge line 26. The latter port may be closed by the enlarged portion 58 on the spool and may be throttled to vary the rate of descent of the ram at the will of the operator, by the tapered portion 59 on the spool.

Port 51 is closed by check valve 61 here shown with a hollow cylindrical body provided with a valve tip 62 adapted to seat on seat 49 and close port 51. The valve is held against its seat by the back pressure in line 33 which communicates with the interior of the valve through a restricted port 63 (Fig. 8).

The check valve also embodies a pilot valve 65 here shown in the form of a ball adapted to seat and close a small port 66 in the tip of valve 61. The ball is held on its seat by a cylindrical valve member 67 slidable inside valve 61 and having a projection 68 adapted to bear against the ball. An orifice 69 in the valve member admits pressure fluid to the interior of the valve so that the entire valve member both inside and out is subjected to the action of the pressure fluid and therefore substantially balanced. A relatively light spring 71 holds the ball on its seat.

Though valve 61 is held on its seat by a substantial unbalanced force created by the pressure fluid on the interior of the valve, the pilot valve 65 may be unseated with little force. In the present instance, the pilot valve is unseated by a pin 72 whose restricted end 73 passes through port 66 and is adapted to engage the ball. Pin 72 is operated by the cam surface 74 upon longitudinal movement of the spool. When ball 65 is thus unseated, fluid pressure inside the valve may exhaust through port 66 into return line 53 at a rate much faster than flow of pressure fluid into the interior of the valve through the restricted orifice 63. The result is that the pressure drop inside the valve is sufficiently great to be overbalanced by the pressure of the fluid against the annular end 76 of the valve around port 51. Valve 48 thus opens and connects line 33 from the ram with the passage 54 leading

to discharge port 57. The tapered portion 59 on the spool is so located in relation to the cam surface 74 that after the pilot valve is opened, the tapered portion 59 on the spool may be employed to throttle discharge port 59 and thus regulate the rate of descent of the ram.

Maximum rate of descent is advantageously limited by interposing in line 33 a regulator valve 77 (Fig. 6). The regulator valve is adjusted to limit the rate of descent of the ram to a safe speed regardless of the load on the ram. For light loads or no load, the rate of descent of the ram is equally rapid since the valve automatically adjusts itself to permit a constant rate of discharge. For descent at a rate less than the maximum rate, the spool is adjusted to throttle orifice 57 by means of the tapered portion 59 on the spool as aforesaid.

The illustrative regulator valve comprises a hollow cylindrical member 78 slidable inside the body of the valve and having an inlet orifice 79 communicating with line 30 leading from the ram and adapted to create a pressure drop tending to move the valve member 78 in the direction of flow. Flow from the regulator valve occurs through ports 81 throttled by the movement of valve 78 against the spring 82. Ports 81 communicate with the annular space 83 around the valve which in turn communicates with passage 33 leading to discharge. For high pressures, the pressure drop in orifice 79 is sufficient to cause a greater throttling of ports 81 than for the lower pressures existing when the ram is only lightly loaded. Conversely, for lighter pressures, a greater port opening is required to permit the pressure drop necessary to counterbalance spring 82, which accordingly moves the valve to increase the port opening. As here shown the valve is seated in a transverse bore 84 in the valve block in which it is sealed by sealing rings 85 and held by lock ring 86. The bore is intersected by bore 33. While the illustrative regulator (these details are fully disclosed in our co-pending application) is simple and inexpensive in construction and well adapted for incorporation in the valve block in association with the several control elements, it will be understood that the invention is not limited to the specific type of regulator herein disclosed.

The illustrative valve device thus embodies in one unit control means by which the ram is elevated and permitted to descend at rates determined by the operator while avoiding descent at unsafe speeds or slow descent with light loads, together with devices for positively locking the ram in extended position under load and preventing the control device of such load and preventing leakage and creeping of the ram which would otherwise occur.

The spool operating mechanism is here shown in the form of a control rod 87 longitudinally slidable in the body of the valve block parallel to spool 21 to which it is connected by the transverse yoke 88. Stops 89 and 90 limit the movement of the control valve, and therefore the spool, in both directions. Neutral position of the spool (wherein the pump discharges at no load) is advantageously easily located and held against accidental displacement by a catch here shown in the form of a spring pressed ball 91 adapted to seat in a notch 92 in control rod when the spool is located in neutral position. The faces of notch 92 are advantageously beveled or tapered to open the catch when the control rod is purposely moved. The end of the control

rod is advantageously threaded as at 93 for attachment of an appropriate operating handle or other mechanism.

Obviously the invention is not limited to the details of the illustrative device since these may be variously modified. Moreover it is not indispensable that all features of the invention be used conjointly since various features may be used to advantage in different combinations and sub-combinations.

Having described our invention, we claim:

1. A control unit for a ram and ram cylinder wherein the load on the ram tends to return the latter to initial position comprising in combination a valve housing having therein a valve chamber and passages leading to said valve chamber and adapted to be connected respectively to the ram cylinder, to a source of fluid pressure, and to discharge; a throttling control valve in said chamber adapted selectively to connect the pressure source with the ram cylinder passage and with the discharge passage, said control valve having means for adjustably throttling flow from said ram cylinder to discharge, a check valve in said ram cylinder passage to prevent return flow from said ram cylinder through the latter passage, a by-pass around said check valve and leading to said valve chamber, a by-pass check valve in said by-pass having means actuated by said control valve to open said by-pass check valve, the latter valve being normally closed to flow from said ram cylinder through said by-pass, and means for operating said control valve to open said by-pass valve to connect said ram cylinder to discharge.

2. A control unit for a ram and ram cylinder wherein the load on the ram tends to return the latter to initial position comprising in combination a valve housing having therein a valve chamber and passages leading to said valve chamber and adapted to be connected respectively to the ram cylinder, to a source of fluid pressure, and to discharge; a balanced throttling control valve in said chamber adapted selectively to connect the pressure source passage with either ram or discharge passages, said control valve being adjustable to open said discharge passage fully to permit unrestricted discharge of fluid from said pressure source at no load, a check valve in said ram cylinder passage to prevent return flow from said ram cylinder through the latter passage, a by-pass around said check valve and leading to said valve chamber, a by-pass check valve in said by-pass having means actuated by said control valve to open said by-pass check valve, the latter valve being normally closed to flow from said ram cylinder through said by-pass, said control valve having means for variably throttling flow passing from said by-pass check valve to discharge.

3. A control unit for a ram and ram cylinder wherein the load on the ram tends to return the latter to initial position comprising in combination a valve housing having therein a valve chamber and passages leading to said valve

chamber and adapted to be connected respectively to the ram cylinder, to a source of fluid pressure, and to discharge; a balanced control valve slidably in said chamber and adapted selectively to connect the pressure source passage with the ram cylinder passage or discharge passage and to connect said ram cylinder to discharge, a check valve in said ram cylinder passage to prevent return flow on said ram through the latter passage, a by-pass around said check valve and leading to said valve chamber, said control valve being freely slidable in said chamber and susceptible to leakage under ram cylinder pressures, a by-pass check valve in said by-pass normally closed to flow from said ram cylinder, thereby relieving said control valve of ram cylinder pressure, said by-pass check valve having a pilot actuating valve provided with means engaged by said control valve for opening the pilot valve and thereby opening said by-pass check valve, said control valve having means for adjustably throttling said ram cylinder passage to control the rate of return of said ram, and means for actuating said control valve.

4. A control unit for a ram and ram cylinder wherein the load on the ram tends to return the latter to initial position comprising in combination a valve housing having therein a valve chamber and passages leading from said valve chamber to the ram cylinder, to a source of fluid pressure, and to discharge; a balanced control valve slidably in said chamber and adapted selectively to connect the pressure source passage with the ram cylinder passage or discharge and to connect said ram cylinder passage to discharge, a check valve in said ram cylinder passage to prevent return flow on said ram through the latter passage, a by-pass around said check valve and leading to said valve chamber, a by-pass check valve in said by-pass normally closed to flow from said ram cylinder and through said by-pass, said by-pass check valve having a pilot actuating valve having means engaged by said control valve for opening the pilot valve and thereby opening said by-pass check valve, said control valve having means for adjustably throttling said ram cylinder passage to control the rate of return of said ram, and a regulator valve for the flow through said by-pass for limiting the maximum flow therethrough thereby to limit the maximum return speed of said ram.

WILLIAM WATERMAN.
